184,170

COMBINED DISPLAY AND ADVERTISING SIGN

Louis L. Epstein, Joseph Lederman, and Oscar Parkoff,
Newark, N. J.

Application April 17, 1957, Serial No. 45,777

Term of patent 14 years

(Cl. D1—12)

Figure 1 is a front elevational view of a combined display and advertising sign, showing our new design;

Figure 2 is a rear elevational view thereof;

Figure 3 is a top plan view thereof;

Figure 4 is an elevational view of one end thereof, the other end being substantially the same;

Figure 5 is a horizontal sectional view approximately on the plane of the line 5—5 of Figure 1;

Figure 6 is a transverse vertical sectional view approximately on the plane of the line 6—6 of Figure 1; and

Figure 7 is a transverse vertical sectional view on the plane of the line 7—7 of Figure 1.

We claim:

The ornamental design for a combined display and advertising sign, as shown and described.
